UNITED STATES PATENT OFFICE.

MIRABEAU N. LYNN, OF RISING SUN, ASSIGNOR TO THE AMERICAN ELECTRIC HEADLIGHT COMPANY, OF INDIANAPOLIS, INDIANA.

CUT-OFF VALVE FOR STEAM-ENGINES.

SPECIFICATION forming part of Letters Patent No. 336,862, dated February 23, 1886.

Application filed June 1, 1885. Serial No. 167,291. (No model.)

To all whom it may concern:

Be it known that I, MIRABEAU N. LYNN, of Rising Sun, in the county of Ohio and State of Indiana, have invented certain new and useful 5 Improvements in Cut-Off Valves for Steam-Engines; and I do hereby declare the following to be a full, clear, and exact description of the same, reference being had to the accompanying drawings, forming a part of this specification, and to the figures and letters of reference marked thereon.

This application is filed as a division of my application No. 158,898, filed March 14, 1885; and the invention relates to certain improvements in the construction, arrangement, and combination of the valve-actuating mechanism especially designed for use in connection with the devices as described in said prior application, but applicable to other constructions 20 of engines, as will be apparent.

The manner of constructing and applying my said invention will first be described, and the particular features sought to be covered herein will be pointed out in the claims.

25 In the accompanying drawings, which are designed to illustrate one mode of applying my said invention to practice, Figure 1 is a sectional view of my improved valve-operating mechanism arranged for application to a multiple-cylinder engine. Fig. 2 is a similar view of a modified form of valve. Fig. 3 is a side elevation, partly in section, on the line $x-x$, Fig. 1. Fig. 4 is a detail showing the manner of connecting the cut-off valve to its pitman.

30 Similar letters of reference in the several figures indicate the same parts.

The letter A designates a portion of the main casing, A' one of the piston-cylinders, A² the valve-cylinder, and B the main driving-shaft, 40 said parts being the same as shown in my application No. 158,898.

Three pairs of cylinders, A' A², are employed, all of the same construction, projecting radially, and located at equal distances 45 apart upon the main casing A, within which latter the working parts of the engine are inclosed.

The steam-valve proper, or that by which the cylinders are alternately put into communication with the steam chest or pipe leading

from the boiler and the exhaust, consists of a tubular valve, D, provided with the inlet-ports d and exhaust-ports d', and arranged to reciprocate in the valve-cylinders A². The valve D is divided into two sections by a dia- 55 phragm or piston, E, the outer section opening into the steam-chest d², and the inner communicating with the central chamber, A. Within the valve-cylinder A² is formed an annular chamber, d³, with a passage, d⁴, leading 60 to the cylinder A'. When the valve D is reciprocated in the cylinder A², the steam is admitted to the cylinder A' through the ports d, and exhausted through the ports d' as those ports are brought opposite the chamber d³, as 65 is well understood.

It is my intention that the valves D shall have the widest and best proportioned ports, to freely admit and exhaust steam in the cylinder, and shall also be given a definite and 70 regular movement, and to this end they are arranged to be driven by a fixed eccentric or eccentrics on the main shaft B.

In the present instance two eccentrics, D' D², are employed, set at the same angle and hav- 75 ing the same throw; hence they operate substantially as one eccentric. Two pitmen, d⁵, are employed for each valve D, one extending to the eccentric D' and the other to the eccentric D². The manner of attaching and applying these pitmen is as follows: In the lower or inner end of the valve D are drilled or otherwise formed diametrically-opposite openings or bearings d¹⁰, to receive a boss or pin, d⁶, projecting laterally from the outer end of the 80 pitman d⁵. The boss or pin d⁶ being inserted in the bearing d¹⁰, is retained in place by means of a pin or soft wire, d⁷, inserted through a transverse opening formed in the valve, said wire resting within a circumferential groove 85 in the boss or pin d⁶, and having its ends bent down, as shown. By this method of attaching and securing the ends of the pitmen to the valve I am able to dispense with the usual nuts, screws, &c., which are liable to become loose, 90 and at the same time simplifying the construction and facilitating the attachment and removal of the parts.

The lower or inner end of each pitman is provided with an arc-shaped saddle, d⁸, rest- 100

ing upon the face of the eccentric, the several saddles being held in place by a divided ring, d^1 , resting in a groove, as shown in Fig. 3, and, if desired, a ring or flange, d^2 , may be 5 formed upon the face of the eccentric, and the inner faces of the saddles may be grooved to fit said flange, whereby the pitmen will be more accurately held and prevented from twisting or becoming misplaced.

10 While this method of attachment and guiding the pitmen is believed to be novel and to possess marked advantages, it is obvious that other devices capable of properly and securely retaining the pitmen may be substituted— 15 such, for example, as those shown in my prior application applied to the piston and crank.

Having thus described the piston and valve-operating mechanism, which, as combined, constitute an efficient steam-engine, I will next 20 proceed to explain how a cut-off can be applied, which, without diminishing the pressure of the steam in the steam-chest, or as delivered to the cylinder through the valve D, shall quickly and positively interrupt the flow of 25 steam through the valve at any desired point in the stroke of the piston. The devices shown for accomplishing this object consist, essentially, of the piston E, (when the automatic cut-off is not employed this is fixed and serves 30 only as a diaphragm separating the steam-valve into its two sections, as described,) located within the tubular valve D, and lying normally between the inlet and exhaust ports, a pitman, E', and an adjustable eccentric or 35 driver, E'', for giving the requisite movements to the piston E, as will be described.

The pitman E' can be conveniently attached to the piston E in the following manner: To the center of the piston is applied—as by a screw-threaded connection—a detachable plug, e, in the end whereof is formed a transverse open bearing, e'. The end of the pitman E' is formed with a transverse semi-cylindrical boss or head, e'', adapted to slide endwise within 45 the bearing e', and when in place the two are fastened in position by a pin or soft-metal wire, e', engaging a groove in the head e'', and having its ends bent to prevent accidental withdrawal.

50 It will be observed that the pitman E' is somewhat longer than the pitmen d^1 , and as it passes up between said pitmen and into the valve D it serves as an additional means to prevent the accidental withdrawal of the 55 heads of the said pitmen from the sockets or bearings in the valve D. As, however, the pitman E' when thus arranged obstructs, in a measure, the exhaust-passage, it is found expedient to provide additional passages d^3 through the lower portion of the valve D, (see Fig. 1,) through which the exhaust-steam can escape, said passages supplementing the exhaust through the center of the valve.

The eccentric E'', for actuating the piston E, 65 is preferably located between the eccentrics D' D'', being supported upon the sleeve d^4 .

This sleeve d^4 , secured to the eccentric D', is concentric with the shaft B, and to it is also removably applied the eccentric D'', whereby the several eccentrics are detachably secured 70 together and to the shaft B.

The manner of attaching or applying the several pitmen E' to the eccentric differs somewhat from that employed with the other pitmen, for the reason that as each piston E 75 is subjected to the direct action of the steam in the steam-chest the pressure and friction upon the eccentric would be unduly multiplied. In order to overcome this objectionable feature, I form one of the pitmen E' 80 with a divided collar, e⁵, embracing the eccentric E'', and to this collar I pivot the inner ends of the remaining pitmen, connecting them by a joint similar to that employed for attaching their outer ends to the pistons E, as 85 shown in Fig. 3. As thus arranged, the pressure of the steam upon the several pistons is borne by the collar e⁵, instead of the eccentric, and a practical balancing of the pistons and their connecting mechanism is thereby 90 secured, so that but little power is required to turn the eccentric and actuate the pistons.

The mechanism described constituting the cut-off is designed to operate in the following manner: The three eccentrics D', D'', and E'' 95 are arranged to move with and be revolved by the shaft B. The eccentric E'', which has the same throw as the eccentrics D' D'', being set at the same angle as the valve-eccentrics, the piston E will be moved in unison 100 with the valve D and operate merely as a fixed diaphragm, the admission and exhaust of steam being effected by the valve D alone. When now it is desired to cut off the steam at any point in the throw of the piston, so it 105 may act by expansion only, the eccentric E'' is set forward or in advance of the eccentrics D' D'' the proper distance, the effect of which is to produce at or near the inner and outer throw of the eccentrics a differential movement of the valve and piston. The effect of this differential movement of the piston and valve is to cause the piston E to move outward in advance of the outward movement of the valve D, and while its inlet-ports are opposite the chamber d^3 , thereby covering the inlet-ports on the inner side and cutting off the supply of steam at a point where the valve D would otherwise continue to admit it to the cylinder.

110 In Fig. 3 the eccentric E'' is set at a point on the shaft diametrically opposite the eccentrics D' D'', and in position to cut off at about one-eighth stroke.

115 It will be noticed that the stroke of the valve proper, D, remains the same under all circumstances, opening wide the inlet and exhaust ports, while the piston E, constituting the cut-off, operates quickly. The piston and valve moving in opposite directions and at 120 any desired part of the stroke, according to the position in which the eccentric E'' is placed,

is adapted to cut off the steam-supply, while the exhaust is not interfered with, but remains full and open.

Any appropriate regulating mechanism may 5 be applied for automatically setting and adjusting the movable eccentric; but I prefer to employ that illustrated and claimed in my before-mentioned application.

Owing to the manner of constructing and 10 combining the direct-acting steam-valves and the cut-off valve and their actuating mechanism, I am enabled from the same patterns, and, in fact, from the same organized machine, to construct an engine that is adapted for operation either with or without a cut-off.

As before stated, the piston E, which performs the office of a cut-off valve, serves as a diaphragm to separate the tubular steam-valve D into two sections, the one containing 20 the inlet and the other the outlet or exhaust ports. When it is desired to dispense with the cut-off and its actuating mechanism, the said piston E is fixed in position within the valve D, to do which it is only necessary to 25 secure the said piston to the walls of the valve D by any suitable fastening; or if the governing mechanism alone is dispensed with the eccentric E² may be fastened to the eccentrics D' D², or to the sleeve d'. Thus it will be seen 30 the same structure is adapted for use either with or without the cut-off feature, and the cut-off actuating devices can be applied or omitted altogether without requiring any alteration in the structure of the engine or 35 change or modification of its operating parts.

I claim as new—

1. In combination with the valve-cylinder, the tubular steam-valve having inlet and exhaust ports, as described, the independently-40 moving cut-off piston located within the tubular steam-valve, intermediate the inlet and exhaust ports, substantially as described.

2. In combination with the tubular steam-valve, its connecting-rod, and actuating-eccentric made fast to the main shaft, the cut-off piston or valve operating within said steam-valve, the pitman and its movable driving eccentric, substantially as described.

3. As a means for connecting the steam-50 valve and cut-off to the driving-eccentrics, and in combination therewith, the two pitmen pivotally connected to the steam-valve, and the

pitman pivoted to the cut-off piston, extending between and beyond the point of attachment of the first-mentioned pitmen, substantially as 55 and for the purpose set forth.

4. In a steam-engine, as a means for pivotally securing the pitman to the valve, and in combination with the latter, the detachable plugs provided with the transverse open socket, and 60 the pitman having the transverse pivot adapted to enter said socket, substantially as described.

5. In combination with the pitman, its transverse pivot, and the socket-bearing in 65 the valve, as a means for preventing their accidental separation, the soft-metal pin passing through the bearing and engaging a circumferential groove in the pivot, substantially as described.

6. In combination with the tubular valve having diametrically-opposite sockets in its lower end, the two pitmen, each provided with pivot-pin entering one of said sockets, the cut-off piston situated within said valve 75 and above its sockets, and the pitman fastened to said piston and extending between the pivot-pins of the first-mentioned pitmen, whereby the latter are prevented from becoming accidentally displaced, substantially as 80 described.

7. In combination with the valve-cylinder having the steam-chest and collars forming the annular chamber communicating with the engine-cylinder, the perforated tube passing 85 through said collars, and the tubular valve composed, essentially, of the two open-mouth cup-shaped extensions, and the intermediate piston or diaphragm, substantially as and for the purpose set forth.

8. In a steam-engine such as described, the combination, with the tubular steam-valve and its actuating devices, of the piston located within said valve intermediate the inlet and exhaust ports, whereby said piston is adapted 95 to serve as a diaphragm dividing the steam-valve into the two sections, as described, or by the application of actuating and governing mechanism may serve as a cut-off valve, substantially as described.

MIRABEAU N. LYNN.
